UNITED STATES PATENT OFFICE.

FRANK H. WHITE, OF PHILADELPHIA, PENNSYLVANIA.

SUIT-CASE.

No. 800,346.

Specification of Letters Patent.

Patented Sept. 26, 1905.

Application filed October 27, 1904. Serial No. 230,189.

To all whom it may concern:

Be it known that I, FRANK H. WHITE, a citizen of the United States, residing at Philadelphia, county of Philadelphia, and State of Pennsylvania, have invented a new and useful Improvement in Suit-Cases, of which the following is a full, clear, and exact description, reference being had to the accompanying drawings, which form a part of this specification.

My invention relates to traveling-bags, and is of particular utility in its application to traveling-bags having square corners, such as dress-suit cases.

The object of my invention is to provide a metallic protective corner-piece to be used in conjunction with a leather corner-piece, whereby the leather piece is effectively held in place and the metallic pieces act as corner-protectors, both alone and in conjunction with the leather corner-piece, thereby protecting the most vulnerable part of the suit-case from injury due to careless handling and hard usage.

A further object of the invention is to provide a metallic protective corner-piece of such character that used in conjunction with a leather corner-piece will enable the latter to be formed of small pieces of scrap-leather that heretofore have been discarded as waste, thereby entirely eliminating the considerable item of expense heretofore attaching to the production of the leather corner-pieces.

In the drawings, Figure 1 is a perspective view of one form of the invention applied to the corner of a suit-case. Fig. 2 is a section on the line 2 2 of Fig. 1. Fig. 3 is a perspective view of another form of the invention applied to the corner of a suit-case. Fig. 4 is a section on the line 4 4 of Fig. 3. Fig. 5 is a detailed view of one of the sections of the leather corner-piece.

a designates a portion of the top of the case, *c* a portion of the end, and *b* a portion of the side.

e (in Figs. 1 and 2) is the leather protective piece, made of three wings or sections, adapted to overlie, respectively, those portions of the top or bottom, the end, and the side of the case that immediately adjoin a corner.

The corner formed at the junction of the three sections is rounded. This leather strip may be of the usual construction, or it may have a portion of each of its three sections embossed or in relief, as hereinafter described.

The protective metallic corner-piece shown

in Figs. 1 and 2 is composed of three arms, which in the direction of their length extend from a common center in three directions, each at right angles to the other two. Each arm is bent along its longitudinal center to form the two integral members *f f* at right angles each to the other. The corner edge formed at the junction of these members is rounded, and the corner formed at the junction of the three arms is likewise rounded.

At the end of each member *f* the same is enlarged, and the enlarged end is provided with a hole for the reception of a rivet *h*.

The leather corner-piece is applied loosely in the usual manner to any particular corner, and the metallic corner-piece is placed upon the leather corner-piece and the rivets inserted through the holes provided for them in the ends of the arms. The rivets also pass through the leather corner-piece and the body of the case. This protective metallic corner-piece holds the leather corner-piece firmly in position and prevents the latter from becoming detached. When used in connection with the leather corner-piece, the metal need not be thick, as it alone is not relied on to protect the corner, its functions being to hold this leather piece permanently in position and to act in conjunction with the leather piece as a protector.

In Figs. 3 and 4 a protective metallic corner-piece of somewhat different form is shown. This piece also consists of three arms each bent longitudinally to form the members *i i*, which correspond to the members *f f* of the preferred form. The ends of the members *i i* are not, however, enlarged or provided with rivet-holes; but the end of each member *i* of one arm is united with the end of a member *i* of another arm by means of a connecting-strip *k*, which is preferably curved to conform to the curved edge of the leather corner-piece. Each connecting-strip is enlarged intermediate of its ends and there provided with a rivet-hole through which a rivet *m* is passed, said rivet also extending through the leather corner-piece and the case-body. The outer edge of the strip is preferably provided with an inwardly-extending flange *n*, against which the outer edge of the leather corner-piece abuts.

In the construction shown in Figs. 3 and 4 I have shown the leather corner-piece made up of three separate pieces *o o o*, (one of which is shown in Fig. 5,) each one of which is of a size somewhat larger than necessary to cover the space surrounded by one of the connecting-

- strips *k* and the members *i i* of the arms united by said strip, the edges of the leather sections *o* extending underneath the said members and connecting-strip. A composite leather corner-strip of this character presents all the appearance of the unitary leather corner-strip *e*, (shown in Figs. 1 and 2;) but it is obvious that it can be formed from small pieces of leather that would otherwise go to waste.
- 10 While I have shown a unitary leather corner-piece in the embodiment of my invention illustrated in Figs. 1 and 2 and a corner-piece made up of three small pieces of leather in the embodiment of my invention illustrated in 15 Figs. 3 and 4, it is obvious that either the unitary or the composite leather corner-piece may be used in either embodiment of my invention or in any other specific embodiment thereof that the skilled mechanic may devise.
- 20 I prefer to make the leather corner-strip with portions thereof embossed or in relief, so as to cause the leather to project upwardly outside the arms in the construction of Figs. 1 and 2 or within the space inclosed by the 25 arms and connecting-strip in the construction shown in Figs. 3 and 4, so that the top surface of the leather will lie substantially flush with the top surface of the arms or the top surface of the arms and connecting-piece.
- 30 Any suitable rigid material may be used in making the outside protective corner-piece, although I prefer the use of metal, and of the various metals brass. Any suitable material may be used instead of leather, and when the 35 body of the suit-case is made of one of the well-known substitutes for leather I may use such substitute material to make the underneath or flexible corner-piece.
- Having now fully described my invention, 40 what I claim, and desire to protect by Letters Patent, is—
1. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 45 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the 50 leather corner-piece being exposed within the spaces inclosed by said arms and wings.
2. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 55 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the leather corner-piece being exposed within the spaces inclosed by said arms and wings, said wings having enlarged portions provided with rivet-holes whereby both corner-pieces 60 may be riveted to the case-body.
3. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 65 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-pieces having enlarged portions provided with rivet-holes whereby both corner-pieces may be 70 riveted to the case-body.
4. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 75 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the 80 leather corner-piece being exposed within the spaces inclosed by said arms and wings.
5. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 85 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the 90 leather corner-piece being exposed within the spaces inclosed by said arms and wings.
6. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 95 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the 100 leather corner-piece being exposed within the spaces inclosed by said arms and wings.
7. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 105 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the leather corner-piece being exposed within the spaces inclosed by said arms and wings, said wings having enlarged portions provided with rivet-holes whereby both corner-pieces 110 may be riveted to the case-body.
8. As a new article of manufacture, a compound protective corner-piece consisting of a leather corner-piece composed of three sections overlying those portions of the outside of the case adjoining a corner, and a metallic corner-piece having three arms extending from and integral with a solid center, the solid central portion being located at the angle formed 115 at the junction of the three corners and the three arms each being bent longitudinally to form two members partially overlying adjacent sections of the leather corner-piece and each extending longitudinally to the edge of the leather corner-piece, the leather corner-piece projecting beyond the longitudinal edges of the arms, said metallic corner-piece also having wings connecting the extremities of adjacent members of adjacent arms and overlying the edge of the leather corner-piece, the leather corner-piece being exposed within the spaces inclosed by said arms and wings, said wings having enlarged portions provided with rivet-holes whereby both corner-pieces 120 may be riveted to the case-body.

In testimony of which invention I have hereunto set my hand, at Philadelphia, on this 19th day of October, 1904.

FRANK H. WHITE.
